UNITED STATES PATENT OFFICE.

WILLIAM H. DUMAS, OF LEBANON, NEW HAMPSHIRE, ASSIGNOR OF ONE-HALF TO
JOSEPH MOORE, OF LEBANON, NEW HAMPSHIRE.

LOOM ATTACHMENT.

1,392,126.

Specification of Letters Patent. Patented Sept. 27, 1921.

Application filed July 11, 1918. Serial No. 244,453.

To all whom it may concern:

Be it known that I, WILLIAM H. DUMAS, a citizen of the United States, residing at Lebanon, in the county of Grafton and 5 State of New Hampshire, have invented new and useful Improvements in Loom Attachments, of which the following is a specification.

This invention relates to loom attachments and more particularly to means for connecting the picker stick and the sweep stick.

One of the objects is to do away with the lug or sweep strap and the power strap 10 now in use, and to reduce the liability of accidents through breakage of the power strap and the letting down of the sweep strap, causing the unusual and violent movement of the shuttles, the latter flying out 15 or producing defects in the warp.

A further object is to employ for the purpose indicated, instead of leather, canvas, or other similar material, an attachment of metal or of fiber, so constructed and 20 mounted that it permits of accurate adjustment, and also permits of maintaining uniform and even application of the power.

A still further object is to provide an attachment which will obviate the necessity 25 of making bolt holes or the like in the picker stick, causing the weakening of the latter, means also being provided whereby the attachment may be readily adjusted longitudinally of the picker stick.

30 A still further object is to provide a device which will be less expensive, both in regard to the first installation and the cost of maintenance.

In the accompanying drawings:

35 Figure 1 is a fragmentary view in elevation showing a portion of a picker stick and a portion of a sweep stick of a loom with one form of the device applied thereto.

Fig. 2 is a view in elevation looking from 40 the right in Fig. 1.

Fig. 3 is a perspective view showing one of the straps to be connected with the sweep stick.

45 Figs. 4 and 5 show details of construction relating to this form of the device and described below.

The picker stick is designated 10 being pivotally mounted at the lower end as in the usual construction, and the sweep stick 50 is designated 12. A plurality of straps

13 and 14 are each provided with a longitudinal slot 15 for the accommodation of a bolt 16 passing through an aperture near one end of the picker stick, and also accommodating a bolt 39 mentioned below. 60

The bolt 16 is secured by means of a nut 17 engaging a washer 18 carried by the bolt, and a similar washer is provided on the opposite side between the head of the bolt and the strap on that side. The straps 13 65 are each provided with notched portions 13' engaged by corresponding notches in the washer 18 permitting of positive contact when adjustment is secured. The use of a single bolt such as 16 makes it unnecessary 70 to provide a plurality of apertures in the sweep stick, which apertures would weaken the stick and cause breakage, resulting in the loss of time in the operation of the machine. 75

The rear or outer end of each strap 13 and 14 is reduced in width as compared with the body portion of the strap, but is made somewhat thicker and thereby affords sufficient strength for the purpose indicated. 80

The reduced ends of the strap pass through slots 22 and 23 in plate member 24, this plate member having a plane surface 25 passing against one side of the picker stick. 85

Member 24 is preferably of about the width shown as compared with the thickness of the picker stick, and is provided with lugs 26 engaging opposite sides of the picker stick in the manner shown. 90

Member 24 is also provided with apertures for the accommodation of the threaded ends of a staple like device designated 28, the legs of which pass across opposite sides of the picker stick, the arched portion of 95 the staple engaging a groove 29 in a plate 30 having a notched surface 31 which contacts with the adjacent edge of the picker stick 10. The threaded ends of the staple are provided with nuts 32 engaging washers 100 33, the latter contacting with the surface of the plate 24. A set screw 40 engages the picker stick, or otherwise there is no engagement of that stick except a frictional engagement, and therefore no weakening of 105 the stick by making bolt holes therein.

Plate 24 is provided with laterally extending members 35, and 36, and also 37 and 38, apertured for the accommodation of a bolt 39 extending transversely with 110

reference to plate 24 and passing through the slot 15 of each strap 13 and 14. The bolt is provided with a nut or nuts, one of the latter engaging a washer contacting 5 with the edge of one of the offset members referred to, and a similar washer is located between the head of the bolt and the adjacent offset member on that side.

What is claimed is:

- 10 In a device of the class described, a picker stick, a sweep stick, a plate mounted on one side of the picker stick and provided with slots extending longitudinally of the picker

stick and also provided with apertures in approximate alinement with the slots, 15 slotted straps extending on opposite sides of the sweep stick and passing respectively through the slots in the plate, and a staple member passing around the picker stick, and through the apertures in the plate, 20 means for securing the staple to the plate, and means for pivotally connecting the straps with the plate.

In testimony whereof I affix my signature.

WILLIAM H. DUMAS.
